(57) **CLAIM**

The ornamental design for an adhesive bandage as shown and described.

DESCRIPTION

FIG. 1 is a perspective view of a first embodiment of an adhesive bandage of the present invention;

FIG. 2 is a top plan view of the adhesive bandage depicted in FIG. 1;

FIG. 3 is a first side view of the adhesive bandage depicted in FIG. 1;

FIG. 4 is a bottom plan view of the adhesive bandage depicted in FIG. 1;

FIG. 5 is a second side view of the adhesive bandage depicted in FIG. 1;

FIG. 6 is a first end view of the adhesive bandage depicted in FIG. 1;

FIG. 7 is a second end view of the adhesive bandage depicted in FIG. 1;

FIG. 8 is a perspective view of a second embodiment of an adhesive bandage of the present invention;

FIG. 9 is a top plan view of the adhesive bandage depicted in FIG. 8;

FIG. 10 is a first side view of the adhesive bandage depicted in FIG. 8;

FIG. 11 is a bottom plan view of the adhesive bandage depicted in FIG. 8;

FIG. 12 is a second side view of the adhesive bandage depicted in FIG. 8;

FIG. 13 is a first end view of the adhesive bandage depicted in FIG. 8;

FIG. 14 is a second end view of the adhesive bandage depicted in FIG. 8;

FIG. 15 is a perspective view of a third embodiment of an adhesive bandage of the present invention;

(Continued)

FIG. 16 is a top plan view of the adhesive bandage depicted in FIG. 15;
 FIG. 17 is a first side view of the adhesive bandage depicted in FIG. 15;
 FIG. 18 is a bottom plan view of the adhesive bandage depicted in FIG. 15;
 FIG. 19 is a second side view of the adhesive bandage depicted in FIG. 15;
 FIG. 20 is a first end view of the adhesive bandage depicted in FIG. 15;
 FIG. 21 is a second end view of the adhesive bandage depicted in FIG. 15;
 FIG. 22 is a perspective view of a fourth embodiment of an adhesive bandage of the present invention;
 FIG. 23 is a top plan view of the adhesive bandage depicted in FIG. 22;
 FIG. 24 is a first side view of the adhesive bandage depicted in FIG. 22;
 FIG. 25 is a bottom plan view of the adhesive bandage depicted in FIG. 22;
 FIG. 26 is a second side view of the adhesive bandage depicted in FIG. 22;
 FIG. 27 is a first end view of the adhesive bandage depicted in FIG. 22; and,
 FIG. 28 is a second end view of the adhesive bandage depicted in FIG. 22.
 The ornamental design which is claimed is shown in solid lines in the drawings.
 The dot-dash broken lines are shown for the purpose of illustrating environmental structure of the adhesive bandage that form no part of the claimed design.
 In the drawings, the claimed design is defined by the shaded surfaces; broken lines immediately adjacent shaded surfaces represent boundaries of the claim and form no part thereof; all other broken lines depict unclaimed environmental subject matter and form no part of the claim.

1 Claim, 16 Drawing Sheets
